CLAIM

The ornamental design for a shoe upper, as shown and described.

DESCRIPTION

FIG. 1 is a front perspective view of a shoe upper showing my new design;

FIG. 2 is a side view thereof;

FIG. 3 is a rear perspective view thereof;

FIG. 4 is a front perspective view of a shoe upper showing an alternative embodiment of my new design;

FIG. 5 is a side view thereof; and,

FIG. 6 is a rear perspective view thereof.

The broken lines immediately adjacent to the shaded area in FIGS. 1–6 represent unclaimed boundaries of the design. The even-length broken lines in the lower shaded panel in FIGS. 4–6 represent disclaimed stitching that forms no part of the claimed design. The broken lines showing the remainder of the shoe in FIGS. 1–6 are for environmental purposes only and form no part of the claimed design.
